CABLE FASTENER

Torvald A. S. Hagelberg, Sparvstigen 6,
S-435 00 Molnlycke, Sweden

Filed Apr. 23, 1973, Ser. No. 353,518

Claims priority, application Sweden Oct. 23, 1972

Term of patent 7 years

Int. Cl. D8—08

U.S. Cl. D8—230

FIG.1

FIG.2

FIG.3

FIG.4

FIG.5

FIG.6

FIG.7

FIG.8

FIG. 1 is a perspective view of a cable fastener.

FIG. 2 is a vertical side view of the cable fastener shown in FIG. 1.

FIG. 3 is a top view of the cable fastener of FIG. 1.

FIG. 4 is a vertical side view of the cable fastener taken perpendicularly to the view in FIG. 2.

FIG. 5 is a perspective view of a modified form of the cable fastener shown in FIG. 1.

FIG. 6 is a vertical side view of the cable fastener shown in FIG. 5.

FIG. 7 is a top view of the cable fastener shown in FIG. 5.

FIG. 8 is a vertical side view of the cable fastener taken perpendicularly to the view in FIG. 6.

I claim:

The ornamental design for a cable fastener, as shown and described.
